US00D377656S

United States Patent

[19]

Leone et al.[11] **Patent Number:** **Des. 377,656**[45] **Date of Patent:** ****Jan. 28, 1997****[54] SCREEN**

[75] Inventors: **Vincent D. Leone; Kenneth W. Seyffert**, both of Houston, Tex.

[73] Assignee: **Environmental Procedures, Inc.**, Houston, Tex.

[**] Term: **14 Years**

[21] Appl. No.: **48,575**

[22] Filed: **Jan. 4, 1996**

[57] CLAIM

The ornamental design for a screen, as shown and described.

DESCRIPTION

FIG. 1 is a perspective view of a screen according to the present invention;
 FIG. 2 is a top view of the screen of FIG. 1;
 FIG. 3 is a bottom view of the screen of FIG. 1;
 FIG. 4 is a side view of one side of the screen of FIG. 1;
 FIG. 5 is a side view of another side of the screen of FIG. 1 opposite the side shown in FIG. 4;
 FIG. 6 is an end view of the screen of FIG. 1; and,
 FIG. 7 is another end view of the screen of FIG. 1 opposite the end shown in FIG. 6.
